DEVICE FOR DETERMINING SLOPE OF GRAIN IN WOOD VENEERS

Filed June 21, 1946

UNITED STATES PATENT OFFICE

2,436,653

DEVICE FOR DETERMINING SLOPE OF
GRAIN IN WOOD VENEERSJohn P. Limbach and Benson H. Paul, Madison,
Wis., dedicated to the free use of the People
in the territory of the United States

Application June 21, 1946, Serial No. 678,187

2 Claims. (Cl. 33—1)

(Granted under the act of March 3, 1883, as
amended April 30, 1928; 370 O. G. 757)

1

This application is made under the act of March 3, 1883, as amended by the act of April 30, 1928, and the invention herein described, if patented, may be manufactured and used by or for the Government of the United States of America for governmental purposes without the payment to us of any royalty thereon.

We hereby dedicate the invention herein described to the free use of the People in the territory of the United States to take effect on the granting of a patent to us.

This invention relates to measuring instruments having as their purpose the measuring of the slopes of wood grains in sheets of wood veneers.

In grading and inspecting wood veneers, a determination of the slopes of the grains is an important factor. It is known in the art that an excessive slope of grain in a wood veneer reduces the strength of the veneer and makes it more liable to warp with a change in its moisture content. A purpose of this invention is to provide an instrument of simple and light construction capable of rapidly and conveniently determining the degree of slope present through the thickness of a sheet of wood veneer.

For a detailed description of our invention, reference is made to the accompanying drawings in which Figure 1 is a three-dimensional view of the invention and Figure 2 is a vertical section of a part of the device on the line 2—2 of Figure 1.

As shown in the drawing, parallel strips 12 and 13, preferably of a light metal of suitable width and thickness and of unequal length, form a straight edge bar and are held apart at one end by a spacer 14, of like material and suitable thickness, to which the two strips are rigidly secured. Member 15, of metal or other suitable material, is a "T-head" straight edge of conventional size, slidably mounted in space 22 between strips 12 and 13 for longitudinal movement, and is designed to maintain a fixed angle, preferably of 90°, with the said straight edge bar by means of machined depressions in the upper and lower surfaces of the said T-head, the sides of which slidably engage the sides of the strips 12 and 13. One end of a member 16 is secured to the upper surface of strip 12, as shown, its other or free end preferably being even with the free end of strip

12. The fixed end of the member 16 has a thicker portion 16A to provide a slot or recess 26 of suitable height and depth between the member 16 and strip 12. This recess is adapted to receive the narrower tab end of a calibrated transparent plate 11, which is slidably inserted in the recess 26 until its shoulder 27 rests squarely against the free end of strip 12, forming an extension thereof in parallel spaced relation with strip 13. The plate 11 is held in place by the pressure exerted when wing nut 17 is tightened on bolt 29. This bolt is mounted in strip 12 with its head flush with the under surface thereof. In the arrangement as shown, a strip of blotting paper 21, or other material of similar purpose, is empaled upon needle point brads or screws 23 slightly protruding from the upper surface of strip 13 near the free end thereof and is positioned directly under the transparent plate 11. It acts as a recorder strip or transfer sheet to detect or receive impressions of a colored liquid used to penetrate the veneer. Plate 11 has a downwardly tapered hole 18, centrally positioned in that portion forming the extension to strip 12. This hole is of sufficient size to permit the introduction of a colored liquid used in conjunction with this device and to receive the spherical head of an air-pump 19 or device of similar purpose. A thin soft rubber washer 20 surrounds the point of emergence of tapered hole 18 in the under surface of plate 11 and is countersunk therein so as to protrude very slightly below said under surface. Its purpose is to form an air-tight connection between the plate 11 and the upper surface 35 of the sheet of veneer at the point at which the colored liquid is brought into contact with it.

In using our invention for measuring the slopes of grains through the thickness of a sheet of veneer, it is contemplated that different transparent plates will be used for different thicknesses of veneer to be measured and that the concentric circles 28 scribed on each plate will be calibrated for such thicknesses. The circles 28 scribed on plate 11 may be calibrated in any manner desired. However, since the slope of wood grains is conventionally measured in the number of inches of longitudinal distance per inch of rise of the grain, it is convenient to calibrate the circles to give this reading directly. Likewise, it is frequently sufficient in the art to determine

2

the slope of the grain as being more or less than a slope of 1 in 6, 1 in 10, or 1 in 15, where 1 is thickness of the veneer and 6, 10 or 15 are multiples of the thickness. The number of calibrated concentric circles may, therefore, be limited to these three for most purposes, but more may be used if greater accuracy is desired. Accordingly, the formula suggested is

$$X \times Y = R$$

where R is the radius of the circles, X is the thickness of the sheet of veneer, and Y is a multiple of X .

Having selected and inserted in the device the transparent plate calibrated to measure the slope of the grain through the thickness of the sheet of wood veneer to be examined, the said sheet is inserted in space 22, as shown in Figure 2 of the drawings, to a sufficient depth to bring the grain in question under the center of hole 18 in plate 11. In such position, the "T-head" member 15 of the device may be slidably adjusted to engage squarely the edge of the sheet of veneer, thus orienting the longitudinal axis of the device perpendicular to the edge of the sheet of veneer. While in this position, a small quantity of a colored liquid of low viscosity is introduced on the surface of the sheet of veneer through the hole 18 in the plate 11 by means of a dropper or similar device. The penetration of this liquid through the fibers of the veneer is accelerated by means of air pressure applied to the hole 18 by means of the air-pump 19 or other suitable device. In tests, it has been observed that the tendency of this liquid under pressure is to penetrate the fibers of the veneer following the slope of the grain. When penetration has been obtained and the point of emergence of the colored liquid from the under surface of the

veneer is registered upon the blotting paper 21, the sheet of veneer is removed. The spot formed on the blotting paper 21 by the colored liquid is then observed with relationship to the calibrated circles 28 scribed upon the under surface of plate 11 from which the degree of slope may be determined.

Having thus described our invention and its use, we claim:

10 1. An instrument for measuring slopes of grains in wood veneer comprising a straight-edge bar composed of two parallel spaced strips of unequal length, the shorter of the two having attached thereto as an extension thereof a transparent plate bearing concentric circles, said circles being calibrated to indicate the slopes of grains through the thickness of the veneer for sheets of predetermined thickness, said transparent plate having a tapered hole of small diameter at the center of said circles, and an absorbent means used in conjunction with said plate and positioned thereunder.

15 2. A method of determining the slopes of grains in wood veneers with respect to their deviation from the vertical comprising penetrating the veneer with a liquid under pressure, registering the points of entry and emergence of the liquid, and measuring the horizontal distance between the two points as a function of the slope.
